(57) **CLAIM**

The ornamental design for a tire for automobile, as shown and described.

DESCRIPTION

FIG. 1 is a front, left perspective view of a tire for automobile showing my new design;

FIG. 2 is a front view thereof;

FIG. 3 is a left side view thereof;

FIG. 4 is a rear view thereof;

FIG. 5 is a right side view thereof; and,

FIG. 6 is a partial enlarged view of a portion as defined by lines 6-6 in FIG. 2.

The top view and the bottom view are the same as the front view.

The claim is directed to the shaded surface of the tire tread. The portions of the drawings shown in broken lines are directed to the boundary of the design and form no part of the claimed design.
